UNITED STATES PATENT OFFICE.

DAVID CUTLER, OF TROY, NEW YORK.

RECEPTACLE.

1,065,922.

Specification of Letters Patent.

Patented July 1, 1913.

Application filed June 4, 1912. Serial No. 701,504.

To all whom it may concern:

Be it known that I, DAVID CUTLER, a citizen of the United States, and a resident of Troy, in the county of Rensselaer and State 5 of New York, have invented certain new and useful Improvements in Receptacles, of which the following is a specification.

This invention relates to receptacles and particularly to such as are made of paste-10 board or other sheet material.

The object of my improvements is to provide a receptacle of the class specified of simple construction and adapted when open, to stand firmly upon two of its corner edges 15 for the display of the contents of said receptacle.

My invention is illustrated, in its preferred form, in the drawing accompanying this specification, wherein—

20 Figure 1 is a perspective view of my improved receptacle with a portion broken away to better show its construction. Fig. 2 is a similar view of the receptacle open, in display condition. Fig. 3 is a diagrammatic cross section on line 3, 3 of Fig. 1.

My improved receptacle is preferably of parallelepiped form and comprises two members 4, 5, articulated along a diagonal as 6, of one side of said receptacle. Said 30 members may be of wedge shape, or of approximately wedge shape; edges 7, 8, of members 4, 5, respectively, being parallel with diagonal line 6 and with each other. As illustrated, edges 7, 8 overlap each other. 35 When the box is closed, but it is obvious that they might equally well be shorter and meet without overlapping, as do those edges contiguous to the line of articulation 6. When edges 7, 8 overlap, as illustrated, there is

thereby provided spring means for holding the receptacle in its closed position, as those edges are strained out of their normal planes in passing one another, see Fig. 3, when closing the box. This tension tends to hold those parts in contact when the box is closed and to prevent the box from opening without assistance. I also preferably provide said receptacle with lips (as 9 on member 5) inwardly reaching from those corners normal to the line of articulation, so as to properly close those corners of the receptacle. See also lip 10 to member 4.

My improved receptacle is provided with a substantial base, comprising corner edges 11, 12, by which it may be supported in its open condition, thereby fully displaying its 55 contents.

My improved receptacle therefore embodies a substantial and convenient device for storing or shipping goods and also for 60 their ready and adequate display in shop windows, or elsewhere.

I claim:

A receptacle of parallelepiped form comprising two members articulated along a 65 diagonal of one side of said receptacle, each member being composed of two triangular parallel sides and two rectangular sides in angular relation, one of said rectangular sides being longer than the other rectangular 70 side.

Signed at Baltimore, Md., this 25th day of May, 1912, before two subscribing witnesses.

DAVID CUTLER.
